(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is a front view of a display screen or portion thereof with graphical user interface showing the claimed design. The outermost dashed broken lines in the figures show a display screen or portion thereof, and form no part of the claimed design.

The other dashed broken lines, the dot-dash broken lines, and the dot-dot-dash broken lines in the figures show boundaries that form no part of the claimed design.

The faded areas including text, numbers, Chinese characters, icons, background images, or a combination thereof between the dashed broken lines and the dot-dash broken lines in the figures show portions of the graphical user interface that form no part of the claimed design.

The faded areas including text, numbers, Chinese characters, or a combination thereof within the dot-dot-dash broken lines show portions of the graphical user interface that form no part of the claimed design.

The gray horizontal band between the dashed broken lines in the center of the graphical user interface forms part of the claimed design.
